DEVICE FOR FORMING GRINDING WHEELS

Frederick G. Kraft, Springfield, Ohio, assignor
to The Thompson Grinder Company, Springfield,
Ohio, a corporation of Ohio

Application September 8, 1947, Serial No. 772,679

2 Claims. (Cl. 51-5)

1

This invention relates to grinding machines and equipment therefor, and particularly to an improved arrangement for dressing a grinding wheel by a crushing roll and for forming the crushing roll.

In grinding operations on workpieces such as chasing tools for die heads and the like, the manufacturer must produce a great variety of pitches, the most popular sizes being from 6 pitch to 56 pitch. Many other sizes, both standard and special, are also manufactured.

The technique of crush forming a grinding wheel by a crushing roll is particularly adapted for this type of production, but the usual methods of producing rolls, especially in the quantity and variety necessary for this type of production, require the investment of a great deal of capital in rolls or roll grinding machines.

The object of the present invention is to provide an arrangement for producing rolls of the type referred to above in such a manner that the cost of the rolls is greatly reduced.

Another object is to provide an arrangement wherein a roll of any predetermined type can be formed in the fixture in which it is to be used to form the grinding wheel.

Still another object is to provide an arrangement for forming grinding wheel crushing rolls at low cost and in which arrangement the roll forming apparatus is a very inexpensive arrangement.

These and other objects and advantages will become more apparent upon reference to the following description taken in connection with the accompanying drawings in which:

Figure 1 is a partial side elevation of a grinding machine having mounted thereon a dressing fixture and roll forming fixture according to this invention;

Figure 2 is a plan view over the table of the machine shown in Figure 1 showing the dressing and roll forming fixture more in detail;

Figure 3 is a fragmentary perspective view showing one form of shaving tool adapted for use in connection with the fixture shown in Figures 1 and 2;

Figure 4 is a vertical section through a part of the roll forming fixture and is indicated by the line 4-4 on Figure 1;

Figure 5 is a sectional view indicated by the line 5-5 on Figure 2 and shows a shaving mechanism employed in connection with the crushing roll; and

Figure 6 is a section indicated by the line 6 on Figure 5 and showing the clutch mechanism of Figure 5 more in detail.

Referring to the drawings, Figure 1 shows a grinding machine having a bed 10 on which is reciprocably mounted a table 12. The table is adapted for receiving a workpiece supporting fix-

2

ture 14 on which is mounted the workpiece to be ground 16.

Secured to the bed 10 or rigidly mounted adjacent thereto is a column 18 which receives a saddle 20 for vertical reciprocation. Carried in the saddle 20 for transverse reciprocation therein is a wheel head 22 on which is mounted a grinding wheel as on the shaft 26.

The saddle may be adjusted vertically on the column 18 by any suitable mechanism such as by the lead screw and nut indicated at 28, the lead screw of which is adapted for actuation by the hand wheel 30 and the bevel gearing 32.

Mounted at one end of the table 12 is a fixture comprising a first frame part 34 which is stationary on said table and which has journaled therein a shaft 36 on which is mounted the crushing roll 38. Slidably mounted on the frame 34 is a second frame 40 which has journaled therein a shaft 42 which mounts a turret 44. The second frame 40 is guided on the first frame 34 as by the means of the dovetail slide shown at 46 in Figure 4, and is adjustable toward and away from the axis of the shaft 36 by the screw 48 and hand wheel 50 carried on the first frame and screw threadedly engaging the second frame.

Reference to Figures 2 and 4 will show that the turret structure 44 comprises a block 52 which has a plurality of slots 54 therein and in which are mounted the shaving tools 56. The tools 56 are locked in position by any suitable means, such as the set screws indicated at 58.

As will be seen in Figure 1, the shaving tools are adapted for being presented to the roll 38 substantially on the horizontal center line thereof. For selectively indexing the block 52 to bring the shaving tools selectively into position relative to the crushing roll, the shaft 42 carries an arm 60 having a plunger 62 therein the end of which is adapted for entering the holes 64 in the upstanding side plate of the frame 40 in which the shaft 42 is journaled. The block 52 is keyed as at 66 to the shaft 42 and the indexing of the shaft thereby insures that the block 52 will also be indexed through the same angular movement.

The dressing roll 38 must be driven during the time it is being shaved and to this end is keyed as at 68 to the shaft 36. The shaft 36 is then connected through the overrunning clutch mechanism 70 to the worm wheel 72 which is driven by the worm 74 on the shaft 76 which is driven by the gear head motor 78 mounted on the frame 34.

Usually, the crushing roll idles when the wheel is being crushed thereby, and the wheel is driven at low speed in order to provide for the rolling action of the wheel and roll. To this end the overrunning clutch mechanism at 70, best illustrated in Figure 6, permits the roll

to idle in one direction of movement relative to the worm wheel 72. As shown, the worm wheel 72 is connected with the cage 76 of the clutch which has a plurality of spiral shaped grooves 78 therein. Connected with the shaft 36 is the cylindrical block 80 and positioned around the block are the balls 82 which lie within the grooves 78. It will be seen that clockwise rotation of the block 76 in Figure 6 will cause the balls 82 to wedge in the slot 78 and thereby to drive the shaft 36. On the other hand, if the cage 76 is held stationary, then the shaft 36 is free to rotate.

The shaving tools indicated at 56 may have any configuration along the edge thereof but for the purposes of illustration are shown as bearing V threads. A representative tool of this type is illustrated in Figure 3 and it will be seen that the tool can be restored to the original sharpness at any time by grinding off a predetermined amount thereof as indicated at 84 across the working edges of the teeth.

In operation, a blank roll is mounted on the shaft 36. The turret mechanism 44 is then indexed to bring the proper tool into shaving alignment with the blank roll. Thereafter the screw 48 is actuated to bring the shaving tool into engagement with the blank roll. At that time the motor 78 is energized to drive the roll at shaving speed. By forcing the tool against the roll the periphery of the roll will be shaved to the proper configuration. Thereafter the shaving tool is retracted from the roll and the wheel 24 is brought into crushing engagement with the roll. After the wheel has been dressed to shape it may be employed for grinding workpieces which will have the same cross-sectional configuration across their ground surface as the crushing roll which was employed for shaping the grinding wheel.

At any time the roll becomes worn beyond the tolerance limits, the proper shaving tool may be reengaged therewith to true the roll surface. After a predetermined number of shaving cycles, the shaving tool may become somewhat worn and it may be restored by grinding it as shown at 84 in Figure 3.

The turret mechanism has been shown in the drawings as being adapted for receiving four tools but it will be understood that any number of tools could be mounted therein that it was desired to employ. Since each shaving tool is of a different configuration, or, as shown, of a different pitch, then as many forms can be ground on the machine as there are tools in the turret structure. This greatly simplifies the production of several varieties of workpieces because it is only necessary to replace the crushing roll, and sometimes the grinding wheel, in order to prepare for a new work cycle.

The rolls are inexpensively produced from blanks and once formed can be employed for a considerable length of time. As rolls are usually formed on a cylindrical grinder, or purchased from a manufacturer thereof, it will be evident that the arrangement of this invention offers a substantial saving in the cost of the rolls and in the investment necessary in equipment for forming the rolls.

It will be understood that this invention is susceptible to modification in order to adopt it to different usages and conditions and, accordingly, it is desired to comprehend such modifications within this invention as may fall within the scope of the appended claims.

I claim:

1. In a grinding wheel dressing device; a first frame; a second frame slidably mounted in said first frame; a roller journaled in one of said frames with the surface form of the roller in true radial alignment with the complementary surface of a grinding wheel said grinding wheel and roller being relatively movable for contact therebetween; a turret journaled in said second frame; a plurality of shaving tools mounted in said turret angularly spaced and each adapted to engage the roller over its entire width and spaced around the periphery thereof having the complementary configuration in radial alignment with the surface form of said crushing roll; angularly spaced recesses in one side of said second frame; means fixed to said turret for turning therewith and receivable in said recesses whereby the turret may be selectively indexed; and motor means mounted on said second frame and connected to said roller for driving said roller during the shaving thereof.

2. In combination in a grinding machine; a reciprocable table; a grinding wheel for grinding workpieces mounted on said table; a fixture on said table comprising a stationary frame and a frame slidable thereon; a roller journaled in said stationary frame with the surface form of the roller in true radial alignment with the complementary surface of a grinding wheel said grinding wheel and roller being relatively movable for contact therebetween; a turret journaled in said slidable frame upon an axis parallel to said roller; a plurality of shaving tools mounted in said turret angularly spaced and each adapted to engage the roller over its entire width and spaced around the periphery thereof having the complementary configuration in radial alignment with the surface form of said crushing roll; angularly spaced recesses in one side of said second frame; means fixed to said turret for turning therewith and receivable in said recesses whereby the turret may be selectively indexed; means mounted on said stationary frame and connected to said roller for driving said roller in one direction during the shaving thereof; and means freeing said roller from connection to said driving means whereby the freed wheel is independently rotated in the same direction during the dressing of said wheel thereby.

FREDERICK G. KRAFFT.
